VEHICLE SEAT

John S. Fridolph, Middletown, Ohio

Application April 23, 1953, Serial No. 350,543

9 Claims. (Cl. 155—179)

This invention relates to seats and more particularly to vehicle seats.

One of the difficulties with seats of present-day construction is that after a person has occupied the seat for a relatively short period of time the person's spinal column becomes fatigued. I believe that this difficulty arises primarily from the fact that with present-day seat construction the support afforded by the seat for the spine is localized to a great extent at a small area near the base of the spine.

The present invention contemplates a seat construction wherein the supporting surfaces of the seat are designed to distribute the load of an occupant's body more uniformly and to permit the total weight of the person to be distributed over those portions of the human body which nature intended to provide for the purpose of support. Thus in the seat of my construction the back member supports the back of a person seated in the seat from the central hip portion upwardly to the region of the shoulders and the bottom portion of the seat provides a uniform support for the thighs and buttocks of the human body from a line approximately in back of the knee joint rearwardly to a line spaced just forwardly of the base of the spinal column.

In the drawings:

Fig. 1 is a sectional view of a seat constructed in accordance with the present invention.

Fig. 2 is a perspective view of the bottom member of the seat shown in Fig. 1.

Fig. 3 is a sectional view of an other form of seat construction according to the present invention illustrating particularly the construction of the seat bottom.

Fig. 4 is a sectional view of the back member of a seat constructed in accordance with the showing in Fig. 3.

Fig. 5 is a perspective view, partly in section, of the seat bottom shown in Fig. 3.

Figs. 6 and 7 are sectional views of still other forms of seat construction in accordance with the present invention.

Referring to the drawings, there is shown in Fig. 1 a seat which includes a base support 10 on which are arranged a bottom seat member generally designated 12 and a back member generally designated 14. The members 12 and 14 are in the form of seat cushions and are fashioned with a plurality of coil springs such as shown at 16 which may, if desired, be enclosed in burlap pockets 18 as is conventional. The springs 16 are arranged in rows both transversely and longitudinally of the seat. Around their upper edges the spring units are edged by a wire rim designated 20 on the bottom member 12 and 22 on the back member 14. It will be observed that in the seat illustrated in Fig. 1 there are five rows of springs 16 extending transversely of the seat bottom member 12 from the front edge thereof which are approximately of the same height. Likewise, in the back member 14 there are arranged five rows of springs 16 transversely

2

of the seat and spaced adjacently from approximately the upper edge of the seat back.

At the rear edge portion of the bottom member 12 and at the lower edge portion of the back member 14 there are arranged two rows of coil springs 24 which are substantially shorter in height than the other springs 16 of the back and bottom seat members. Accordingly, the wire edge rim 20 is fashioned with a downwardly offset portion 26, and the wire edge rim 22 of back member 14 is fashioned with a rearwardly offset portion 28. These rims are offset in this manner to accommodate the springs 24 of shorter length. The spring units of the back and bottom seat members are overlaid with a padding such as a sponge rubber pad 30 and trimmed with a fabric trim cover 32 so as to present a neat and smooth appearance over the entire supporting surface of the seat.

The present invention is particularly concerned with the seat construction adjacent the rear portion of the bottom member 12 and the lower portion of the back member 14. In the seat shown in Fig. 1 the construction with which this invention primarily relates is at the offset portions 26 and 28 in the supporting surfaces defined by the upper ends of springs 16 and 24. It will be observed, assuming that the spinal column of a person seated in the seat is as shown by dotted lines 34, that the offset portion 26 defines a recess 36 in the supporting surface of the seat which extends rearwardly from a transverse line spaced just forwardly of the hips or the base of the spinal column 34. Likewise, with respect to the back member 14 the offset portion 28 provides a recess 38 which extends downwardly from a point spaced just above the lower end of the spinal column 34. Thus, in the seat construction illustrated a person's body would be provided with a relatively firm support from approximately the knees to just forwardly of the hips by the bottom seat member 12 and from just above the base of the spine to the shoulders by the back member 14. The weight of the person is thus uniformly distributed over the thighs and the buttocks and the upper back portions of the person. The supporting surfaces of the seat bottom and back are relieved at that area which corresponds to the lower end of the spinal column. I have found that the support afforded by the seat construction described is very comfortable and does not fatigue the spinal column nearly as much as a seat which provides a continuous and firm support substantially entirely around the person's body from the knees to the shoulder.

In Figs. 3, 4 and 5 I have shown a seat constructed in accordance with the invention and employing in the place of coil springs such as shown at 16 and 24 in Fig. 1 springs 40 which are commonly referred to in the art as zig-zag springs. These springs are each fashioned from a length of spring wire with spaced apart return bends. The springs 40 are preferably arranged to extend in a direction from front to back on the seat bottom generally designated 42 in Figs. 3 and 5 and in a direction up and down on the seat back generally designated 44 in Fig. 4. Springs 40 of bottom member 42 are each fashioned with a central portion 46 which provides a substantially horizontally disposed supporting surface, and at the rear portion thereof the springs 40 are fashioned with a downwardly offset portion 48 which defines a recess 50 at the rear portion of bottom member 42. Likewise, in the back member 44 springs 40 are each fashioned with a central portion 52 which defines a generally vertically disposed supporting surface, and at the rear portion thereof springs 40 are rearwardly offset as at 54 to define a recess 56 at the lower portion of back member 44. At their opposite ends springs 40 are turned downwardly towards the base of the spring

unit and connected to a bottom frame member such as shown at 58.

The offset portions 48 and 54 are located such as to relieve the supporting surfaces of the seat members in the same manner as described with reference to Fig. 1, namely, at that portion of the seat which corresponds to the area surrounding the base of the spinal column of a person seated in the seat. Preferably the springs 40 are overlaid with a padding such as the sponge rubber pad shown at 60, and the units are trimmed with a fabric trim cover 62. Pads 60 and cover 62, it will be observed, provide a smooth surface over the spring units and cooperate with the offset portions 48 and 54 to define the recesses 50 and 56 in the bottom member 42 and back member 44, respectively.

In Fig. 6 I have shown a further construction in accordance with the present invention. In Fig. 6 it will be noted that there is shown a seat bottom member 64, and it will be appreciated that this bottom member 64 is used in conjunction with a back member (not shown) which is of generally the same construction. The bottom member 64 is in the form of a spring unit comprising rows of coil springs 66, 68, 70, 72, 74 and 76. The rows of springs 68, 70 and 72, it will be observed, are located on the bottom member 64 to correspond in position with the heavy thigh portions of a person occupying the seat. These springs provide a firm support for such thigh portions and are consequently of relatively heavy construction. The springs 66 in the row adjacent the front edge of the seat are of lighter construction than springs 68, 70 and 72 to provide a more resilient support for the area under the knees of the occupant.

The springs 76 in the rearmost row are of relatively light construction, and the springs 74 in the next adjacent row are only slightly heavier in construction. Thus, the rear two rows of the springs of the seat bottom 64 provide a very resilient supporting surface. This area of the seat is designed to provide a very weak support. The rows of springs 74 and 76 correspond to and serve the same purpose as the offset portions 26 and 48 in the seat constructions shown in Figs. 1 and 3, respectively. The row of springs 72 is positioned just forwardly of the hip line of the seat occupant. The seat back usable with the bottom member 64 would be constructed substantially the same as the bottom member 64 with the lower portion of the spring unit provided by relatively weak springs so that when the two seat members are arranged in position, such as the position illustrated in Fig. 1, the seat would provide a relatively firm support for the thighs up to a line spaced just forwardly of the base of the spine and for the upper back portion of the person occupying the seat.

In Fig. 7 there is shown a seat cushion 80 which incorporates the essential feature of this invention. Cushion 80 has an outer trim fabric 82 which encloses the resilient supporting means of the seat. In this instance these means may be in the form of a foam rubber cushion member 84 which is more compressible adjacent its rear end portion 86 than at the forward and central portion of the seat. The rearward portion 86 can be much more compressible by employing a more compressible foam rubber formulation at this portion or, as illustrated, by reducing the thickness thereof.

Thus, it will be seen that I have provided a seat which is designed to provide a comfortable and a non-fatiguing support for the human body. This improved construction is based upon relieving the supporting surface either by way of forming a depression therein or by weakening the supporting surface of the seat at that portion thereof which corresponds to the area surrounding the base of the spinal column of the occupant of the seat. By relieving the supporting surfaces in this manner, the seat is designed to provide a relatively firm support for the thigh portions of the occupant up to a line spaced just forwardly of the hip line and for the back portion

of the occupant extending upwardly from a line spaced slightly above the base of the spinal column and at the same time exerting little or no pressure either vertically or laterally on the lower end of the spinal column.

It will be appreciated that the forms of construction herein shown and described represent only several of many different constructions which may be adopted for accomplishing the purposes of this invention. The basic feature of my seat construction resides in relieving the seat supporting surfaces at those portions thereof which correspond to the area surrounding the base of the spinal column, either by forming recesses or depressions or by providing a relatively weak and highly resilient support at these areas.

15 I claim:

1. A seat for supporting a person in a comfortably seated position comprising a back member and a bottom member arranged to present generally vertically and horizontally disposed supporting surfaces, said horizontally disposed supporting surface being fashioned to provide a relatively firm support over that portion thereof which extends forwardly from a transverse line on the bottom member extending slightly forwardly from the hip line of a person seated normally on said seat, and a relatively negligible support over the remaining portion of said seat supporting surface between said transverse line and the rear edge of said bottom cushion member.

20 2. A seat as called for in claim 1 wherein said bottom member comprises a spring unit overlaid with a layer of padding, the top face of said spring unit defining said horizontally disposed supporting surface, the portion of said supporting surface rearwardly of said transverse line being offset downwardly relative to the portion of said top supporting surface forwardly of said transverse line.

25 3. A seat as called for in claim 1 wherein said bottom member is formed of a resilient compressible material, at least a portion of said material extending rearwardly from said transverse line being substantially more readily compressible than the portion of said material extending forwardly of said transverse line.

30 4. A seat as called for in claim 1 wherein said vertically disposed supporting surface is fashioned to provide a firm support for the back of a person seated in said seat from a line spaced slightly above the base of the spine to the region of the shoulders and a relatively negligible support therebelow to the lower edge of said vertically disposed supporting surface.

35 5. A seat as called for in claim 4 wherein said back member and bottom member comprise seat spring units.

40 6. A seat for supporting a person in a comfortably seated position comprising a back member and a bottom member, said bottom member having a generally horizontal supporting surface and means on said bottom member rendering said horizontal supporting surface compressible over that portion thereof which extends from a transverse line on the seat disposed slightly forwardly of the hip line of a person seated normally on the seat to the rear edge of said bottom member upon application of a force which is negligible relatively to the force required for depressing the portion of said seat extending forwardly from said transverse line.

45 7. The combination set forth in claim 6 wherein said means comprise a plurality of coil springs, the upper ends of which provide said generally horizontally extending supporting surface.

50 8. The combination set forth in claim 7 wherein the springs disposed between said transverse line and the rear edge of said bottom member are designed to flex more readily than the springs located forwardly of said transverse line.

55 9. The combination set forth in claim 8 wherein the springs disposed between said transverse line and the rear edge of said bottom member are of lighter construction

tion than the springs disposed forwardly of said trans-
verse line.
